UNITED STATES PATENT OFFICE.

GEORGE W. WILSON, OF EAST DURHAM, NORTH CAROLINA.

KNITTING-MACHINE ATTACHMENT.

1,406,128.

Specification of Letters Patent.

Patented Feb. 7, 1922.

Application filed June 14, 1921. Serial No. 477,485.

To all whom it may concern:

Be it known that I, GEORGE W. WILSON, citizen of the United States, residing at East Durham, in the county of Durham and

5 State of North Carolina, have invented certain new and useful Improvements in Knitting-Machine Attachments; and I do declare the following to be a full, clear, and exact description of the invention, such as will enable 10 others skilled in the art to which it appertains to make and use the same.

My invention has for its object to provide an extremely simple and inexpensive, yet a highly efficient attachment for knitting machines of the cylinder type which will absolutely prevent any oil on the cylinder or on the inner side of the usual discharge sleeve extending below said cylinder, from soiling the knitted product.

20 A further aim is to provide a device of the character set forth which may be used in connection with well-known knitting machines, without the necessity of making any alteration in the construction thereof.

25 With the foregoing in view, the invention resides in the novel construction and association of parts hereinafter described and claimed, the descriptive matter being supplemented by the accompanying drawings.

30 Figure 1 is an elevation of a knitting machine equipped with one form of my invention, a portion of the latter being in vertical section.

Figure 2 is a vertical sectional view as indicated by line 2—2 of Fig. 1.

Figure 3 is a horizontal sectional view as indicated by line 3—3 of Fig. 2.

Figure 4 is a view similar to Fig. 1 but showing a different form of the invention.

40 Figure 5 is a vertical sectional view on line 5—5 of Fig. 4.

Figure 6 is a detail horizontal section on line 6—6 of Fig. 5.

Figure 7 is a perspective view of the attachment shown in Figs. 4, 5 and 6.

In the drawings above briefly described, I have shown a well known form of knitting machine which comprises a table 1 supporting the usual cylinder 2 and its driving gear 3. The needles are designated by the numeral 4 and their operating cam is indicated at 5, these several parts being operable in the well known manner to form a knitted product 6 which is usually discharged through a sleeve 7 secured to the table 1 and depending therefrom. Proper lubrication of the nee-

dles 4 and associated parts often causes a quantity of oil to collect on the inner side of the cylinder 2 near its lower end, and some of this oil runs down the inner side of the 60 sleeve 7, so that there is danger of forming oil spots on the product 6, as it is discharged. This is very undesirable since any portion of the product which is oil-soaked will not properly take the dye when the dyeing operation is performed. Oil-soetting of the product is prevented by my invention, which I have shown in two forms for knitting short or long hose or the like. In Figs. 1, 2 and 3, the numeral 9 designates a vertical elongated casing received within the sleeve 7 and provided at its upper end with a neck 8 extending upwardly into the cylinder 2 so as to receive the product 6 and guide it into the casing 9 without permitting said product to 65 contact with the cylinder or with the sleeve 7. The casing 9 is relatively long and is intended for use when long hose or the like is being knitted and the casing in question is preferably increased gradually in size at its 70 lower end, which end is equipped with a laterally extending portion 9^a whose top is formed with an opening 10 by means of which the work may be removed. A flange 11 inclines from the inner edge of the opening 10 and serves to prevent any oil which might possibly accumulate on the top of the extension 9^a from entering the casing through the opening 10.

Any suitable means may be employed for 90 securing the attachment in place, but I prefer to equip it with a pair of metal strips 12 and 13 through which screws 14 are passed, said screws being threaded into the lower end of the sleeve 7.

95 Figures 4 to 7 disclose the form of my invention which is employed when knitting relatively short work. In these figures, the numeral 20 designates a vertically elongated casing positioned totally within the sleeve 7 100 and provided with a reduced inlet neck 21 to extend upwardly into the cylinder 2 as shown in Fig. 5. One side of the casing 20 is provided with an opening 22 for registration with the usual opening 23 in the sleeve 105 7 and the uppermost and vertical edges of said opening 22 are provided with metal flanges 24 (preferably formed of lead) which are adapted to be bent outwardly along the corresponding edges of the opening 23 (see 110 Figs. 5 and 6). These flanges form guards to prevent any oil running down the inner

side of the sleeve 7, from possibly entering the casing 20 through its opening 22. One of the flanges is secured to the sleeve 7 by appropriate screws 25.

5 From the foregoing, taken in connection with the accompanying drawings, it will be seen that I have provided a very simple, yet a highly efficient and desirable device to absolutely prevent oil-staining of the knitted 10 product as it is discharged from the machine. Excellent results have been obtained from the details disclosed and they are therefore preferably followed. I wish it understood, however, that within the scope of the invention as claimed, numerous minor changes 15 may be made. Furthermore, for adapting the attachment to different types of machines, it may be manufactured in numerous forms other than those disclosed.

15 20 I claim:

1. The combination with a knitting machine, of a receiving casing for the knitted product having an inlet neck extending upwardly into the cylinder of said machine to 25 prevent the product from coming in contact with any oil on said cylinder, said casing having a closed bottom and an outlet opening, and a guard to prevent any oil on the exterior of said casing from running into the 30 latter through said opening.

2. The combination with a knitting machine having a sleeve extending below its cylinder and provided with an opening in one side, of a receiving casing for the knitted 35 product positioned in said sleeve and having

an opening registering with the aforesaid opening, and flanges on said casing bent outwardly around the edges of said first named opening, said casing having an inlet neck extending upwardly into said cylinder of 40 the knitting machine.

3. An attachment for knitting machines comprising a receiving casing for the knitted product having an outlet neck adapted to extend upwardly into the cylinder of a knitting machine, said casing having a closed bottom and being provided with an outlet opening, and a guard to prevent oil on the exterior of the casing from running into said casing through said opening. 45

4. An attachment for knitting machines comprising a vertically elongated tubular casing having an inlet neck at its upper end adapted to extend upwardly into the cylinder of a knitting machine, said casing being adapted for reception in the usual sleeve of the machine and having an outlet opening for registration with an opening in the aforementioned sleeve, and a flange on said casing at the edge of its opening adapted 50 to be bent outwardly around the edge of the sleeve opening.

In testimony whereof I have hereunto set my hand.

GEORGE ^{his} X W. WILSON.
